Patented Nov. 19, 1918.

UNITED STATES PATENT OFFICE.

STEFAN ORBAN, OF NEW YORK, AND JAMES T. MCNAIR, OF BROOKLYN, NEW YORK.

TOOL FOR FACILITATING THE REGRINDING OF IGNITION CONTACT-POINTS.

1,285,344.

Specification of Letters Patent. Patented Nov. 19, 1918.

Application filed June 20, 1917. Serial No. 175,836.

To all whom it may concern:

Be it known that we, STEFAN ORBAN, a native of Hungary, residing at New York, county of New York, State of New York, and JAMES T. MCNAIR, a citizen of the United States, residing at Brooklyn, county of Kings, State of New York, have invented certain new and useful Improvements in Tools for Facilitating the Regrinding of Ignition Contact-Points, of which the following is a specification.

The present invention relates to means for facilitating the regrinding of ignition contacts such as used in magnetos or primary circuits of ignition systems, particularly of the kind known in the trade as Delco tungsten contacts.

It is a well felt disadvantage of such contacts, that, after a comparatively short use they fail to operate by reason of the fact that the contact surfaces burn or wear off and become uneven. The contact points as now in use are permanently fixed in holders, of which one is known in the trade as breaker arm and the other as contact screw, one breaker arm and screw constituting a complete set for a magneto or primary circuit of an ignition system. When the contact surfaces become uneven owing to burn or wear, the entire set or a part of the set has to be discarded and replaced, which owing to the comparatively high price adds materially to the upkeep of a machine. On the other hand, the removal of the worn contact points and their replacement by new ones, involves labor, the cost of which is about the same as that of a complete piece or set. Attempts have been made to regrind the surfaces of the contact points, but owing to the lack of a proper tool for holding the parts have not been successful, since even with the most skilled and steady hand, it is impossible to hold the parts perfectly even on the grindstone.

The object of our invention therefore, is to provide a tool in which both, a breaker arm and screw or several sets can be properly supported so that during the grinding process, they will rest evenly on the grinding stone and will not be affected by the shaking of a hand.

Another object of our invention is to so construct the tool as to hold breaker arms and contact screws of various sizes, and give it thus the character of a universal tool for this purpose.

A further object is to provide means to enable the adjustment of the contact holders according to the position required.

With these and other objects in view our invention consists in the construction, arrangement and combination of parts as will be hereinafter more fully described and set forth in the appended claims.

In the accompanying drawing which forms part of this specification and in which similar reference numerals designate corresponding parts in the different figures, Figure 1 is a rear elevation of the tool; Fig. 2 is a longitudinal section on line 2—2 of Fig. 1; Fig. 3 is a bottom plan view of the device; Fig. 4 is a side view thereof; Fig. 5 is a cross section on line 5—5 of Fig. 1; Fig. 6 is a cross section on line 6—6 of Fig. 1; and Fig. 7 is a modified form of construction of the plate holding the breaker arms and Figs. 8 and 9 denote modified forms of holders for contact arms.

In the example shown the contact holders are of the type known as the Delco contacts which comprise a set of two, one consisting of an arm B which at one end has permanently fixed to it the contact point c and the other consists of a threaded pin C having at one end a head in which the contact point c' is permanently fixed. But while our tool is particularly designed for the regrinding of contacts of the Delco type the same is equally applicable to contacts of other types of similar construction but different sizes.

The tool consists of a frame made of brass or other suitable material and which comprises a base portion 1 having a smooth and even bottom 2 in which are provided a cross groove or cross grooves 3 extending throughout the width of the bottom and one or more substantially circular holes 10 projecting upwardly from the base are arms or posts 4 for the fastening of a handle 5 made, as shown, of a piece of metal bent upon itself and formed with a rounded upper surface to form a convenient grasp. At the rear the base is provided with ribs 1', which project downwardly below and at a right angle to the bottom 2 and the front surfaces 1" of which are also smooth and even, to form guide surfaces as will be hereinafter more fully described. Projecting rearwardly from the base are flat members in form of plates 6 in which are suitably mounted members 8 in form of circular disks or the like so as to be

capable of turning on central axes running longitudinally of the base. To each of these disks is eccentrically fixed a pin 9 extending parallel to the base and at some distance 5 away from and transversely to the cross groove 3. The axes of these pins are substantially even with the bottom of the grooves 3. Owing to their eccentricity relative to the disks 8, they can be adjusted to 10 extend a trifle higher or lower from their original position. These pins serve as supports for the perforated ends of the breaker arms B, the same being so admeasured in diameter as to loosely fit in the circular holes 15 b of the arms B. The contact ends of the breaker arms B when applied are adapted to extend through or into the cross grooves 3 with their contact points projecting sufficiently outwardly from the grooves, so that 20 when the tool is applied with its bottom to a grinding surface they will be in contact with and acted upon by the latter. In order that these ends of the arms may be retained in the grooves 3 during the handling of the 25 tool the grooves may be admeasured to snugly or with a slight friction engage the contact ends of the arms B, or in order to allow for variation in sizes or to compensate for wear a screw pin 12 having a cam shaped 30 head 12' may be used which with its head projects into the groove 3 through a recess 3', so that an adjustment of the width of the groove may be possible. Of course the said 35 adjustment may be obtained by any other suitable means.

Since the holes b in the arms B may also vary in diameter, instead of solid pins 9 split pins or springs 9' (Fig. 8) may be used. As the contact points c, c' are usually not 40 very thick pieces and it is not desired to grind off more of their surfaces than actually necessary to even them up, these points must be so supported in the grooves as to yield vertically so that when the even 45 bottom of the tool is placed onto and moved over the grinding surface only the uneven parts of the contact surfaces will be ground off. To accomplish this we provide a spring member 7 which may be fixed to or mounted 50 on a projecting pin of the frame and which will extend across the grooves 3 so as to engage the upper surfaces of the contact ends of the arms B when the same are inserted into the grooves 3. The spring will have the 55 tendency to press the contact ends outwardly in the measure as they are being ground off until their surfaces are perfectly even with the surface of the bottom 2 of the tool.

For securely holding the pins 9 in adjusted position, the disks 8 may be provided with locking arms 8' which are adapted to engage ridges or furrows 6' arranged on the plates 6 radially relative to the disks 8.

The circular hole or holes 10 in the base 65 serves for the accommodation of a member

11 formed with a threaded bore 11' into which the threaded pin C forming the other holder of the set of contacts is supported. This member 11 is likewise acted upon by a spring 7' suitably supported in the frame 70 and serving to form a resilient rest for the contact point c'. The upper end of the member is somewhat enlarged forming a shoulder 11' which will rest on the top of the base and thus prevent the member 11 75 from falling out from the hole 10.

In moving the tool over the grinding surface the guide ribs 1' with their even surface 1' may be held in contact with a side surface of the grindstone so as to afford a rectilinear 80 movement of the tool. As there are some breaker arms in use which instead of holes b have pins for their support in the magneto, the plates 6^a may be provided with perforations 6^b instead of with pins 9, so as to form 85 sockets for the pins of the breaker arms. A number of such perforations will enable the support of breaker arms of various length. Our tool is primarily designed to hold the two contact pieces of a set, so that the grinding 90 of the set may be performed at once. But it is of course clear that it may have two or more cross grooves for the contact ends of several breaker arms and also a number of circular bores for several contact 95 screws.

The construction described is only one embodiment of our invention which may be variously modified without departing from the spirit of our invention. We therefore, 100 do not wish to restrict ourselves to the details described and shown.

What we claim and desire to secure by Letters Patent is:

1. A tool for facilitating the regrinding 105 of ignition contacts on a grindstone, comprising a hand piece having a grooved level bottom and sockets therein for such contacts and means in said sockets for supporting a contact in said bottom during the grinding 110 process.

2. A tool for facilitating the regrinding of ignition contacts on a grindstone, comprising a hand piece having a level bottom with sockets therein for said contacts and means in said sockets for resiliently supporting said contacts in said bottom during 115 the grinding process.

3. A tool for facilitating the regrinding of ignition contacts on breaker arms, comprising a hand piece therefor having a level bottom with a groove therein to engage the contact end of said arm and means on said piece for the removable support of the other end 120 of the arm during the grinding process.

4. A tool for facilitating the regrinding of ignition contacts on breaker arms, comprising a hand piece therefor having a level bottom with a cross groove therein to engage the contact end of said arm, means in 125

said groove to form a resilient rest for said end and means on said hand piece to removably support the other end of said arm during the grinding process.

5. A tool for facilitating the regrinding of ignition contacts on breaker arms, comprising a hand piece therefor having a level bottom with a cross groove therein to engage the contact end of said arm, means in 10 said groove to resiliently support said end, and adjustable means on said hand piece to removably support the other end of said arm.

6. A tool for facilitating the regrinding 15 of ignition contacts on breaker arms, comprising a hand piece therefor having a level bottom with a cross groove therein to engage the contact end of said arm, a guide piece projecting from said bottom to guide 20 said hand piece rectilinearly along one side of a grind stone, and means on said piece for the removable support of the other end of said arm.

7. A tool for facilitating the regrinding 25 of ignition contacts on breaker arms, comprising a hand piece therefor having a level bottom with a groove therein to engage the contact end of said arm, an eccentrically pivoted member on said piece to removably 30 engage the other end of said arm, and means to resiliently support in said groove the contact end of said arm.

8. A tool for facilitating the regrinding 35 of ignition contacts on breaker arms, com-

prising a hand piece to support said arm while grinding, having a cross groove to engage the contact end of said arm, an adjustable pin on said piece to removably support the perforated end of said arm and means for resiliently supporting in said 40 groove the contact end of said arm.

9. In a tool of the character described, a hand piece having a level bottom with grooves therein for the engagement of contact holders, a resiliently supported member 45 in one of said grooves to engage one of said contact holders, resilient means extending across the other groove to serve as a rest for the contact end of another contact holder and means on said hand piece to removably support the other end of said last 50 named contact holder.

10. A tool of the character described, comprising a hand piece having a level bottom to bear evenly on the grinding surface, 55 a guide piece to guide said hand piece rectilinearly along one side surface of the grind stone and means on said hand piece for supporting contact holders during the grinding 60 process.

In testimony whereof, we affix our signatures in presence of two witnesses.

STEFAN ORBAN.
JAMES T. McNAIR.
